UNITED STATES PATENT OFFICE.

MOSES G. FARMER, OF SALEM, MASSACHUSETTS.

IMPROVEMENT IN SELF-ACTING ELECTRIC TELEGRAPHS.

Specification forming part of Letters Patent No. 15,373, dated July 22, 1856.

To all whom it may concern:

Be it known that I, M. G. FARMER, of Salem, in the county of Essex and State of Massachusetts, have invented certain new and useful Improvements in Electro-Magnetic Printing Telegraphs, of which the following is a full, clear, and exact description, reference being had to the accompanying drawings, making part of this specification, in which—

Figure 1 is a plan, Fig. 2 an elevation of the back, Fig. 3 an elevation of the front, of the instrument, the letter-wheel being removed to show the parts behind, its position being indicated by the circle *q* in red; Fig. 4, a vertical section upon the line A³ A³ of Fig. 1, with part of the frame removed; Fig. 5, details, which will be hereinafter referred to. Fig. 6 is a diagram exhibiting a view of a telegraphic circuit containing the essential operating parts of two instruments.

My invention consists in the use of a circuit-wheel of peculiar construction, the segments of which are connected with the operating keys so as to form alternately open and closed circuits, and in certain details employed in the carrying out of the first part of my invention, which will hereinafter be particularly described.

I will first indicate the course of the current through the instrument when the machine is in operation, then describe the general construction and operation of the machine, and, lastly, the features which form the subject of my present improvements.

The current from the battery enters the machine at A through the wire *x*. Thence it passes to magnet M at *a*. At *b* it leaves the magnet and passes by the wire *c* to the framework B of the instrument, which, together with the other operating parts, is insulated upon the wooden table C. The current leaves the instrument through the shaft D of the type-wheel by the circuit-wheel spring *d*, from which it passes to the segments *i i'* of the circuit-wheel; thence through the wires F G to the key-anvils *f g*. Through the anvils *f* and the corresponding keys the circuits remain closed. Through the anvils *g* and their keys the circuits are open. From these anvils the current passes by the keys A B C D, &c., to the metallic bar L; thence along the key marked B *r* to its anvil *h*, (the circuit here being closed); thence by the wire *k* to

the screw-cup H, where it leaves the machine.

When the machine is not in operation the current is allowed to pass directly from the instrument at the point *l*, at which it enters, to the switch S *w* by the wire *z*, and without passing through the circuit-wheel. This switch is represented in Fig. 1 as open, the current consequently taking the previously-indicated course through the circuit-wheels and keys. When, however, the switch (which is capable of motion around the point *m*) is thrown into contact with the metallic bar I, as seen in red in Fig. 1, the current passes directly through the wire *n* to the bar L; thence by the break-circuit key B *r* and wire *k* to the screw-cup H, as before.

The course of the current from the local battery which actuates the printing-magnet will be indicated hereinafter.

The manner in which motion is communicated to the circuit-wheel will now be described.

The weight W is suspended by the cord N from a barrel, O, of the shaft of the wheel P. This weight is wound up by a key upon the projecting end *r* of the shaft, the wheel P being connected with the barrels by the pawl S and ratchet-wheel T, that the position of the machinery may not be altered by the winding up of the weight. The wheel P engages with the pinion R upon the shaft of the wheel S, which engages with a pinion, *t*, (seen dotted in red in Fig. 4,) upon the shaft D of the letter and printing wheels. The wheel U upon this shaft drives a pinion, *a'*, upon the arbor V of the escapement, the operation of which, in connection with that of the circuit-wheel, will now be described. The body of this wheel Q is made of some insulating substance, hard india-rubber being preferred, metallic segments *i i'* are let into the body of the wheel, as seen in Fig. 2, and are thus entirely insulated from the instrument. The segments *i* are connected by the wires F with the anvils *f* of the closed keys, and the segments *i'* are connected by the wires G with the anvils *g* of the open keys. An arm, *b'*, secured to the shaft D of the letter-wheel, carries a spring, *d*, which rests in succession upon the segments *i i'*. The number of the segments corresponds with the number of letters or characters employed. In the present instance there are twenty-eight.

In Fig. 5 is represented the operation of the escapement B' and its connection with the magnet M . Two of its arms carry pins c' , which are at a less distance from the center than the pins d' of the other arms. These pins rest upon the pallet A' , the latter being vibrated so as to receive alternately the pins c' and d' by the making and breaking of the circuit.

When the machine is not writing the switch S w is in the position seen in red in Fig. 1, the current proceeding in the manner already indicated without passing through the circuit-wheel, the armature C' remaining in contact with the magnet M . When the switch is in the position seen in black in Fig. 1, the current is caused to pass through the instrument and circuit-wheel, and the operation is as follows: Commencing at the instant when the spring d is resting upon one of the segments i' , which is connected by its wire G with the anvil g of one of the open keys, the current is now interrupted and the armature C' is drawn away from its magnet M by the spring D' . This motion of the armature (Fig. 5) liberates one of the pins, c' , of the escapement from the pallet and the latter is thrown into a position to catch and retain the next pin, d' , of the escapement, which is thus allowed to rotate ninety degrees. This motion of the escapement is sufficient to allow the spring d to pass onto one of the segments, i , communicating by its wire F with the anvil f of one of the closed keys, by which the circuit is again closed and the magnet M charged. The armature C' is now attracted to it, and the pallet A' is moved so as to let off the pin d' of the escapement and catch the next one, c' . This allows the spring d to pass onto the next segment, i' , of an open circuit, and thus the armature C' , being no longer attracted by its magnet, is drawn back again by its spring shifting, as before, the pallet A' , and permitting the escapement to revolve another quadrant, as before, and thus the spring d , and with it the letter-wheel, is caused to revolve continuously so long as the battery continues in operation.

The spring d and segments i i' must be so adjusted to each other that the spring shall touch the succeeding segment before it leaves the segment which it may at any time be on; for when the key of an open segment is pressed down three contiguous segments are closed, and the escapement, not being let off by the motion of the armature and pallet, the circuit spring stops. If, however, there were an instant during the passage of the spring from one of these segments to another when it touched neither of them the circuit would be broken, the armature would fly back and release the escapement, and the spring would pass on without stopping. Two similar instruments, arranged as above at opposite ends of a magnetic line, when once placed in correspondence—that is, with their springs d upon similar segments of the circuit-wheel—will continue thus in correspondence, the letter-wheel in each being moved forward a

single letter by each breaking or closing of the circuit.

I will now explain the method by which the impression is taken off upon the strip of paper whenever the letter-wheel is allowed to remain momentarily stationary.

The letter-wheel, as before stated, is removed from its shaft (Fig. 3) to show the parts behind it. It does not differ essentially from those heretofore employed, and need not therefore be described. Upon the shaft of the letter-wheel is secured the printing-wheel E , having types upon its periphery corresponding in number and character with the letters of the letter-wheel. These types are so arranged that the type that is brought into position to be printed from shall correspond with the letter presented to view by the letter-wheel. When the printing-wheel is arrested the impression is taken therefrom in the following manner:

F' is the printing-magnet, its armature K' being held suspended therefrom by the spring G' , Fig. 4.

H' is a lever attached to the armature and pivoted to the frame at j' at the opposite end. This lever carries the printing-hammer I' , which lies immediately beneath the printing-wheel E' , Fig. 1, and as the armature is drawn down upon its magnet the hammer is thrown up against the projecting face of the type, an impression of which is transferred to the paper L' , which is guided into the machine upon the curved metal strips M' N' , the latter having a hole at g' , through which the hammer passes as it strikes the paper up to the printing-wheel. The paper is fed forward through the machine between the rolls r^2 l' , which are operated (Fig. 4) after each impression is made by the pawl O' , pivoted to an arm secured to the lever H' .

The hammer is arranged like the hammer of a clock-bell, so as to spring away from the type-wheel so soon as the blow has been given.

I will now explain the manner in which the magnet F' is caused to act. For this purpose a local battery, Q' , is employed, the current from which enters the machine by the wire h' to the screw-cup R' , whence it passes by the wire k' to the magnet F' . From the magnet it passes by the wire m' to the frame of the machine, and to the dropping pallet S' . The other wire, n' , from the local battery enters the machine at the screw-cup T' , which is connected with the pin p' by the wire q' . This pin projects from an ivory block, r' , or is otherwise suitably insulated from the machine, from which it is evident that when the pallet S' is raised from contact with the pin p' the current will be broken and the magnet F' will not be charged. When, however, the pallet S' is allowed to rest upon the pin p' the current is closed, the armature K' drawn down, and the hammer is projected against the type-wheel. The types are inked by the ink-roll W' , which rests lightly upon their faces, as seen in Figs. 1 and 4.

continues in operation it should remain inactive. This is effected in the following manner: The pallet S' rests upon the wheel U , secured to the shaft of the printing-wheel. When this pallet is borne upon one of the teeth s' of the wheel U , it is raised out of contact with the pin p' . When, however, it falls between two of the teeth s' it descends so low as to come in contact with the pin p' , by which the circuit is completed and the magnet is caused to act. During the continuous revolution of the printing-wheel and cog-wheel U , the pallet S' is caused to make such momentary contacts with the pin p' , that there is not time sufficient to bring the magnet into operation. When, however, the printing-wheel stops the pallet falls between two of the teeth s' and closes the circuit. It is necessary that the number of the teeth on the wheel U be some multiple of the number of segments in the circuit-wheel.

It now remains to describe the manner in which the motion of the letter-wheel and printing-wheel is arrested by the manipulation of the keys A B C , &c.

Suppose the machine to be in operation and the key I to be depressed, the circuit through this key and its anvil f and wire F , which before was closed, is thus opened, and on the arrival of the spring d at the corresponding segment i it finds the circuit broken, and the armature C' is not attracted to its magnet M , but remains as seen in Fig. 2 so long as the key I remains depressed. On this key being released the printing-wheel is again allowed to revolve, as before. If now one of the open circuit-keys— L , for instance—be depressed, the circuit through this key, which before was open, is now closed, and on the arrival of spring d at the segment i' , in connection with the anvil g' of this key, it finds the circuit closed, and the armature C' remains in contact with its magnet, and the spring d again remains stationary until the key is relieved, the hammer rising each time a key is depressed to give the impression of the type upon the paper, as before.

Should the operator at the receiving-station discover that the instruments are not regulated in correspondence with each other, he depresses the break-circuit key B_r , by which means both instruments are stopped, whereby notice is given to the operator at the other station that something is wrong. He then proceeds to bring them into accordance with each other by means of the following device: An open key, R_g , called the "regulating-key," is employed for the purpose. The anvil q of this key is connected with the screw-cup A by the wire p . The key itself is connected by means of the wire a^2 with an insulated pin, t' , in the face of the circuit-wheel Q . This pin carries a spring, c^2 , which projects within the path of the arm b' . The spring c^2 has not sufficient strength to arrest the motion of the arm, but on coming in contact therewith when the regulating-key R_g is depressed a new path is opened for the current, which it takes without passing through the magnet, and the arm b' is arrested, and with

it the letter and printing wheels. The machine is so arranged that when thus arrested the spring d shall always fall upon the segment corresponding to the key $-$, (dot.) The receiving-machine is thus stopped upon this key; but as the current is only turned out of the receiving-magnet and not broken the transmitting-machine continues in operation. The operator at the latter station then depresses his key $-$, (dot,) by which his instrument is also stopped upon this key. It is necessary, however, that he hold this key depressed until the operator at the other end of the line has time to relieve his regulating-key. Otherwise the transmitting-machine would proceed without the other, and the desired end would not be attained. After the lapse of a few seconds the operator at the receiving-station releases the regulating-key, and then when the key (dot) is relieved at the other station the two machines proceed together.

By means of the wires F and G , I am enabled to employ a straight key-board with a circuit-wheel placed in any desired position without the use of the complicated system of levers that would otherwise be necessary to connect the two.

Operation: When neither station is transmitting the switch S_w of each instrument is turned into the position represented in red in Fig. 1. The current then passes from the screw-cup A , through the magnet M , by the wires c and z , to the switch S_w and bar L ; thence by the bar L , key B_r , anvil h , and wire k to the screw-cup H . The current not passing through the circuit-wheel is not broken, and the magnet remains permanently charged. When the operator at one end desires to transmit he moves his switch S_w into the position seen in black in Fig. 1, by which the current is thrown through the circuit-wheel of his machine, whereby the circuit is made and broken, and the armatures of both magnets are set in operation, and the circuit-springs, letter-wheels, and printing-wheels of both instruments revolve together. The operator at the transmitting-station then sends his message through the keys A B C , &c., the current passing through the transmitting-instrument, as follows: from the screw-cup A by M c B D d , segments i or i' , wires F or G , to the bar L , and by the key B_r , and wire k to the screw-cup H . Through the receiving-instrument it passes from the screw-cup A by the magnet M , thence by the wires c and z to the switch S_w and bar I , and by the wire n to the bar L , back to the screw-cup H , as before.

I do not claim arresting the motion of the type-wheel by a positive stop upon the key, which interrupts the motion of the wheel whenever a key is depressed, and at a moment when the circuit is broken, as in the telegraph of Siemens & Halske's; but

What I do claim as my invention, and desire to secure to by Letters Patent, is—

1. The method herein described of arresting the motion of the type-wheel by means of the

alternately open and closed keys, in combination with the circuit-wheel, constructed and operating in the manner substantially as herein set forth.

2. The combination of a straight key-board with a circuit-wheel, when the two are connected together by means of the wires F and G, whereby the place of making and breaking the circuit may be transferred to the immediate vicinity of the key-board, for the purpose set forth.

3. The method herein described of putting the two machines in correspondence with each other, the current being turned out of the operating-magnet M of the receiving-machine by means of the regulating-key Rg, the arm b', insulated spring e², and their connection, operating in the manner substantially as set forth.

MOSES G. FARMER.
